CLAIM

The ornamental design for an electric wing actuator as shown and described.

DESCRIPTION

FIG. 1 is a front, right and top perspective view of an electric wing actuator, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the electric wing actuator, shown in an environment of use.

The broken lines depict portions of the electric wing actuator that form no part of the claimed design. The unshaded surfaces between solid and broken lines in FIGS. 5 and 6 form no part of the claimed design. The additional broken lines shown in FIG. 9 illustrate environmental subject matter only that form no part of the claimed design.
